AIR DRYING MEANS FOR SCREEN PRINTING APPARATUS

Harry Fleisher, Watertown, Conn., and George H. Tillett, Jackson Heights, N. Y., assignors to Roto-Matic Screen Printer, Ltd., New York, N. Y., a corporation of New York

Application September 6, 1941, Serial No. 409,867

15 Claims. (Cl. 101—420)

This invention relates to apparatus for applying designs upon flexible webs of textile fabrics, paper, and like materials, and more particularly to an improved apparatus employing a stencil-printing screen.

This invention is an improvement over a screen printing apparatus disclosed in a prior Patent No. 2,210,474, issued August 6, 1940, to George H. Tillett, entitled "Color printing web."

This application is a continuation in part of 10 our prior application, Ser. No. 364,604, filed November 7, 1940, entitled "Screen printing apparatus."

One object of this invention is to provide improved means to space the coils, or layers, of 15 printed web from each other when they are wound upon a spool, and for permitting the flow of a stream of dry air between the layers of said web after the printing operation.

A further object of this invention is to provide an improved apparatus for applying designs upon flexible webs of the above nature, which will be relatively inexpensive to manufacture, simple in construction, easy to operate by relatively unskilled labor, compact, ornamental in appearance, and very efficient and durable in use.

With these and other objects in view, which will appear as the description proceeds, there have been illustrated in the accompanying drawings several forms in which the invention may be conveniently embodied in practice.

Briefly, the screen printing apparatus of this invention includes a central table for supporting a screen, frame and a pair of spools, one carrying a roll of web to be printed, and the other serving as a take-up roll for the web after printing. The web to be printed is adhesively fixed to a carrier belt which is fed manually intermittently from one spool below the screen to be wound upon the other spool. Provision is also made of marginal spacer strips secured to the carrier belt so that when said belt is wound in spiral condition, the color paste freshly printed upon the web will be kept out of contact with the adjacent layer of said web, whereby smudging of said color will be prevented, and said fresh color will be given a chance to dry. The spacer strips also serve to separate the successive layers of the web and provide between them a drying space through which a stream of dry air may be forced.

By winding the printed web in spiral form upon the take-up spools, the material may be stored while drying or curing in the minimum of space as compared to the former methods of 55

drying printed webs on elongated flat tables or suspending said webs in festoons or loops. The compact coiled web-carrying spools of the present invention are movably mounted on casters so as to facilitate the feeding of the web back again through the printing apparatus for applying additional colors or printing the web at different areas from those originally printed.

In the drawings:

Figure 1 is a front elevational view of an improved screen printing apparatus embodying the invention.

Figure 2 is a broken end elevational view of the same.

Figure 3 is an enlarged broken sectional view on line 3—3 of Figure 2 across one side of the machine.

Figure 4 is a broken perspective view of the web and the carrier belt and spacing strips therefor.

Figure 5 is an edge view of a short length of a web, a carrier belt, and a spacer strip of modified form having teeth on the bottom surface thereof.

Figure 6 is a view similar to Figure 5, of a web, a carrier belt, and still another modified form of spacer strip having eyelets instead of teeth secured thereto.

Figure 7 is a cross-sectional view of a spool 30 showing a web carrier belt, and the modified form of spacer strip shown in Figure 5 wound thereon.

Figure 8 is a longitudinal sectional view of a spool having a web carrier belt and a spacer 35 strip of the form shown in Figure 5, wound thereon, and showing means to direct a flow of dry air through the layers thereof.

Figure 9 is a broken side view of the machine showing a modified form of web guiding 40 means.

Figure 10 is an end view, with parts broken away, of a motor-operated fan mechanism for blowing a stream of drying air longitudinally through the layers of the helical belt carrying the freshly printed web wound upon the spool.

Figure 11 is a fragmentary view of the same, and one end of the spool.

Figure 11a is a fragmentary view of the other end of said spool.

Figure 12 is an edge view of a short length of a web carrier belt spacing strip having a series of modified spacer buttons of streamlined form mounted on the underside thereof.

Figure 13 is a bottom view of the same.

Figure 14 is a fragmentary view of a screen

printing apparatus, showing a modified form of belt and spacing strips in which the belt passes above the table top and the spacing strips pass beneath it.

Figure 15 is a fragmentary view of the same showing a side view of the guiding means for the spacer strips located beneath the table top.

Referring now to the drawings wherein like reference numerals designate like parts throughout the several views, the numeral 10 denotes a flat table top which, in this instance, is suitably supported by four corner uprights, or legs 11, 12, 13, and 14. The uprights 11 and 12 are connected and braced by horizontal bars 15, 16, and 17, while the rear uprights 13 and 14 are likewise connected and braced by similar horizontal bars located behind said bars 15, 16, and 17, and concealed thereby as viewed in Figure 1. The uprights 12 and 13 are connected and braced at the top by horizontal side bars 18, 19, and 20, and the uprights 11 and 14 are braced by similar side bars concealed thereby. At each end of the apparatus, provision is made of upright bars 21 extending from the lower horizontal bar 15 to the upper bar 17, and a short vertical bar 22 extends at each side from the intermediate horizontal bar 19 to the lower bar 20 (Figure 2).

Provision is also made of a pair of horizontal shafts 23 mounted in and extending between the uprights 11 and 12, and the uprights 14 and 13, respectively. Each of said shafts 23 is journaled at each upright 11, 12, 14, and 13, in brackets 24 (Figures 1 and 2), each of which is vertically adjustable on and is secured to the respective upright by a bolt 25 passing through an elongated slot 26 provided in the bracket 24 and screw-threaded into the respective upright. A hand wheel 27 is secured on the front end of each shaft 23 and a sprocket 28 is secured upon the rear end of said shaft. The shafts 23 are extended at their front ends 29 beyond the uprights 12 and 13, and said ends are preferably made hexagonal in cross-section to removably receive a manually-operated crank handle 30.

The table top 10 extends rearwardly beyond the uprights 11 and 14, as at 41 and is provided with a pair of transversely spaced apart bearing brackets 32 and 33 adjustably mounted thereon by means of bolts 34 and 35 passing through a common elongated slot 36 in each bracket and through the table top extension 31 (Figure 2). An angle piece 37 secured to the table top extension 31 has a screw 38 threaded therethrough into engagement with each of the brackets 32 and 33 to permit them to be held in any desired position and to prevent said brackets from moving rearwardly when the machine is being operated.

Stencil screen

Provision is also made of a swingable stencil-supporting frame (Figures 1 and 2), comprising end rods 39 and 40, and side bars 41 and 42, the rear end rod 40 being pivoted in bearings 43 and 44 carried by the brackets 32 and 33 respectively. The rods 39, 40, 41, and 42 are connected together at the corners of the stencil frame by four angle blocks 45, thus maintaining the frame in rectangular shape.

Four vertically disposed posts 46 extend upwardly, one from each angle block 45, to support side rods or tracks 47 and 48, which are spaced above the side rods 41 and 42, respectively, and are parallel thereto. An elongated angle bar 49 extends between the side rods 41 and 42 adjacent the front end of the screen supporting frame,

and a similar angle bar 50 extends between the rods 41 and 42 adjacent the rear ends thereof. The angle bars 49 and 50 are adjustably secured to the respective rods 41 and 42 by clamping brackets 51, and are arranged to have one of their angle portions horizontal and the other vertical. By means of the brackets 51, the angle bars 49 and 50 may be adjusted longitudinally in the direction of web travel along the rods 41 and 42 to position the stencil frame supported thereby in the desired location.

The horizontal base portions 52 of the angle bars 49 and 50 extend toward each other and form opposing seats for a rectangular stencil screen, which, in this instance, is made of four narrow wooden strips 53, 54, 55, and 56, and secured together at their adjoining ends. A printing stencil sheet 57 is stretched across the bottom of the stenciled screen, said sheet 57 being preferably made of specially treated silk having the desired perforated design formed thereon through which the thin color paste may penetrate and be applied by a squeegee to the web W placed thereunder. In this instance, the front and rear strips 53 and 55 of the stencil screen are removably seated on the horizontal portions 52 of the angle bars 49 and 50 of the swingable stencil screen supporting frame.

The stencil frame, comprising the strips 53, 54, 55, and 56, is seated in the carrying frame, comprising the bars 39, 40, 41, and 42, and may be brought into exact register with the design on the stencil screen by adjustment of the vertical limit arm 58 (see Figure 2), of an adjustable guide bar having a horizontal arm 59 which is secured to the table top 10.

The stencil screen, 53, 54, 55, and 56, may be manually-lifted from the underlying web W whenever it is desired to shift the web, by swinging its carrying frame 39, 40, 41, and 42, upwardly about the hinged connection of the rod 40 in the bearings 43 and 44 as a pivot.

Provision is also made of means to manually lift the stencil screen carrying frame, 39, 40, 41, and 42, and such means comprises a pivoted foot treadle 80 which, as shown in Figure 2, is connected to the front rod 39 of the screen carrying frame through a system of links and levers arranged with a "mechanical disadvantage" whereby a comparatively small movement of the treadle 80 will move said frame a relatively large amount.

The foot treadle 80 is pivoted at 81 to a cross bar 82 extending between the lower side bars 20, and provision is made of a short upstanding link 83, which loosely connects the forward part of the treadle 80 with a long vertical link 84. The upper end of the long link 84 is loosely connected to a short vertical link 85, which in turn is pivoted to an inclined arm 86 at a point closely adjacent the lower fixed end 87 thereof. The end 87 of the arm 86 is pivoted to the front intermediate upright 21 between a pair of angle blocks, and the upper end 90 of the arm 86 is connected by a chain 91 (see Figure 2), reeved over a pulley 92, supported on the rear surface of the upright 21, said chain passing downwardly from said pulley and being connected to a post 93 secured to a vertical slide 94, which is adapted to loosely embrace the upright 21.

The slide 94 is connected to the lower end of an upstanding plate 95 (Figures 1 and 2), which carries a short horizontal shaft 96 at its upper end. The shaft 96 extends beyond the sides of the plate 95 and has rollers 97 journaled on each end thereof. The rollers 97 engage blocks 98

secured to the underside of the front screen frame rod 39 and serve to reduce friction. By means of this construction, it will be seen that when the operator steps on the treadle 80, force will be transmitted through the links 83, 84, 85, arm 86, chain 91, slide 94, plate 95, to the rollers 97, causing the front end of the stencil screen carrying frame to swing upwardly and lift the stencil screen out of contact with the web W. To assist the operator in this operation, counterweights 98 may be hung upon the arm 86 adjacent its upper end 90. The stencil carrying frame is engaged at its forward end by a pair of curved strips 154 and 155 which serve to guide the angle blocks 45 as this frame is lowered into place.

The web W is adapted to be fed across the table top 10 under the stencil screen 57 from one side of the printing apparatus to the other. In order to avoid any stretching or movement of the web W, it is temporarily secured upon a carrier band or belt 100, preferably constructed of heavy flexible paper, by means of a nondrying, sticky adhesive which may be composed, for example, of a mixture of china clay and glycerine. By the use of this adhesive, the carrier belt 100 may be used repeatedly before replacement is necessary, due to the fact that it may be stripped therefrom repeatedly without damage to the belt 100 of the web W. In most instances only the outer fibres at the undersurface of the web W are impregnated by the adhesive.

Provision is also made of a pair of spacer strips 101 and 102 disposed beneath both margins of the carrier belt 100, and preferably cemented thereto (see Figure 4). It will be understood that said strips 101 and 102 may, if desired, be riveted to the carrier belt 100 as by eyelets, within the scope of the invention. The combined web W, carrier belt 100, and spacer strips 101 and 102, are adapted to be guided across the table top 10, by means of a pair of transverse grooves 103 and 104, respectively, formed in the upper surface of said table top 10. When the web W and the carrier strip 100 are wound into a spiral coil upon a spool 105 (as shown in Figures 1 and 2), it will be understood that the belt 100 will be spaced apart in successive layers by the strips 101 and 102 at its edges, thus providing an air space therebetween, protecting the color paste printed on the web W and preventing "smudging" of the table top 10 thereby. The color will thus be permitted to penetrate uniformly into the web and produce a sharp and distinct reproduction of the design thereon. The edges of the web carrier belt 100 outside the web are preferably coated with shellac or other suitable material to seal them against moisture and afford additional stiffening.

The color paste employed in the screen printing apparatus is adapted to be forced through perforations in the stencil screen 57 onto and into the web W by means of a squeegee blade 106, preferably made of soft rubber and having its upper edge set into a recessed strip 107. The strip 107 is hinged as at 108 to another strip 109, located above it, which strip 109 is adapted to be clamped between a pair of transverse angle bars 110 and 111 by a pair of thumb screws 112. The angle bars 110 and 111 are secured to the forward ends of a pair of short horizontal slide members 113 and 114 of inverted U-shape in cross-section. The legs of each inverted U-shaped member straddle the parallel side tracks 47 and 48 and thus guide the squeegee blade 106

in its manual reciprocation by the operator who grasps a relatively long handle rod 115 secured at one end to the cross bars 110 and 111, as shown in Figures 1, 2, 3, 4, and 5. It will be noted that the inverted U-shaped guiding members 113 and 114 do not actually rest on the tracks 47 and 48, but the weight of this structure and the squeegee blade 106 is imposed directly upon the stencil screen 57 so as to cause the color paste to pass therethrough and upon the web beneath it. The pressure of the squeegee blade 106 upon the screen may be increased if desired by the use of suitable ring shaped weights 116 surrounding a pair of vertical posts 117 extending upwardly from the guide members 114.

In operation, the squeegee blade 106 will be lifted at each end of its stroke and moved and lowered at the opposite side of the mass of color paste so as to push it in the reverse direction. This operation is readily accomplished by swinging the handle rod 115 upwardly and causing the rear ends 119 and 120 of the guide members 113 and 114 to engage the tracks 47 and 48 which act as fulcrums therefor.

When the printing operation is completed, the squeegee blade 106 will be raised away from the stencil screen 57 and maintained in such raised position, while the stencil screen is also lifted and the web shifted to bring a new unprinted portion into registry with the screen. For this purpose, provision is made of a pair of transversely spaced apart standards 121 and 122 secured to the table top 10 at the rear of the stencil screen supporting angle bar 50. Each of the standards 121 and 122 has a horizontal rearwardly extending arm 123, 124, and forwardly extending angle arm 125, 126, respectively. The arms 123 and 124 extend outwardly in opposite directions and carry rollers 127, and the arms 125 and 126 extend inwardly toward each other and carry rollers 128.

When it is desired to support the squeegee blade 106 up out of contact with the stencil screen 57 at the rear end of its stroke, it will merely be necessary to tilt the handle 115 upwardly to cause the rear ends 119 and 120 of the guide members 113 and 114 to be disposed under the rollers 127, and the rear cross bar 111 to be disposed above the rollers 128. The web-carrying belt with the web W adhering thereto may then be fed across the table top 10 from the feed spool 105 on one side of the printing apparatus to the take-up spool 105 on the other side. Each of the spools 105 has a hollow shaft 129 which extends from its rear end, and has a sprocket 130 detachably secured to said extending end by a set screw 131. A chain, 132, is reeved over the sprocket 130 and the sprocket 28 on the hand wheel shafts 23, whereby rotation of the hand wheel 27 on the take-up side of the apparatus will cause the web W to be fed across the table top 10 from the feed spool 105.

In order to insure accurate printing, indicating lines are marked at spaced intervals along the edge of the carrier belt 100, and a single line is marked on the table top 10. These marks when in alignment indicate to the operator that the web W has been properly positioned in accurate registration for another printing operation.

70

Spools

As herein shown, a pair of identical spools 105, are provided which may be selectively used for "feeding" and "taking-up" of the web. Each spool is permanently mounted upon a truck 135

having casters 136 whereby it may be wheeled toward and away from the apparatus to carry the web into and out of printing position. In order to insure accurate registration of the printed designs on the web, means are herein provided on each side of the printing apparatus for alining the spool carrying truck 135 with said apparatus. The alining means above referred to includes two pairs of resilient arms 137, 137a extending outwardly from the corner uprights 12, 13, and 11, 14. The arms 137, 137a are each curved outwardly to facilitate the movement of the side base bars 138 and 139 of the truck 135 into engagement therewith and to guide the feeding spool so that the web W to be printed will be in correct transverse registry with the stencil screen when it is fed into printing position.

In order to lock the spool truck 135 in operating position, provision is made on each of said alining means of a toggle mechanism comprising a lever 140 having one end pivoted as at 141 to the adjacent resilient arm 137, 137a. A handle 142 at the other end of the lever 140 is provided to manipulate the same. Provision is also made of a thin rod 143 having a hooked end 144 adapted to catch into an elongated slot 145 provided in the side base bars 138 and 139 and pivotally secured to the lever 140 intermediate its ends, said rod 143 passing through a vertical post 146 which is arranged to rotate in the lever 140. A coiled spring 147 surrounds the rod 143 and reacts between the post 146 and a washer held on the outer end of the rod 143 by lock nuts 149 and 150. When it is desired to hold the truck in the locked position, the hooked end 144 of the rod 143 will be connected to the truck side bars 138 and 139 by engagement in the slot 145 nearest thereto and the levers 140 will be swung into the truck-loading position. If desired, an additional slot 145 may be used so that the trucks may be readily reversed and either side thereof selectively applied to the printing apparatus.

Web-drying apparatus

While the apparatus is being operated, and a freshly printed web W is being wound continually upon the take-up spool 105, a constant flow of dry air will be directed against the surface of the web on said spool by means of a duct 151 leading from a central motor driven air blower 152 (see Figure 1). Additional drying may also be obtained by means of an auxiliary blower, not shown, to force dry air into the hollow spool shaft 129, which air will be caused to flow outwardly through perforations 153 therein and between the layers of the spiral coil of web W wound thereon.

In the modified form of web-drying means illustrated in Figure 5, a continuous row of spaced-apart teeth 160 are provided on the underside of the spacer strips 161 and 162, which strips are similar in other respects to the plain spacer strips 101 and 102, shown in Figure 4. In Figure 6, the teeth consist of spaced-apart eyelets 163 attached to the spacer belts and having openings 164 therebetween.

It will be seen from these modified forms of spacer belts, shown in Figures 5 and 6, that a stream of dry air under pressure may be supplied to a special form of spool 165 having a hollow shaft 166 which is plugged adjacent one of its end flanges 167, as shown in Figure 8. The hollow shaft 166 outside of the flange 167 is provided with perforations or slots 168, to permit the dry air stream to pass outwardly into a hollow end casing 170 which is suitably secured in spaced

relation at its outer edge to the flange 167 to form an enclosed chamber. The flange 167 is also provided with a series of arcuate slots 171 in alignment with the openings 164 between the teeth 160 or eyelets 163 on the spacer strips 161 and 162, whereby the stream of air blown into the casing 170 will be forced in a longitudinal direction through the successive layers of the web W spirally wound on the spool 165.

Operation

The operation of the above described screen printing apparatus is substantially in accordance with that disclosed in the above-mentioned Patent No. 2,210,474. In brief, the operation is as follows:

Assuming the squeegee blade 106 is held in raised position by the rollers 127 and 128, the stencil screen frame will be swung upwardly by depressing the treadle 80. The web-carrying belt 100 will then be drawn across the table top 10 from the feeding spool 105 with the spacer strips 101 and 102 guided by the grooves 103 and 104, respectively. The free end of the web-carrying belt 100 will then be attached to a take-up roll 105, which has first been locked in place at the other side of the printing apparatus, by threading it through the slot 172 in a longitudinal bar 173 of the take-up spool, as indicated in Figure 7. The hand wheels 27 will then be turned to bring the first mark on the carrier belt into alignment with the mark on the table top 10, whereupon the stencil screen holding frame will be lowered to cause said screen to engage the web W. The squeegee blade 106 will then be lowered upon the rear end of the stencil screen 57 and the proper quantity of color paste will be then placed upon the screen 57 in front of the blade 106, which may then be pulled forwardly by means of the handle 115.

When the squeegee blade 106 is in its forward position after having traversed the length of the screen 57, it will be lifted by tilting the handle 115 upwardly and placed in front of the mass of color paste, and then pushed rearwardly to spread the same along the screen 57. After the desired number of strokes of the squeegee blade 106 have been made, said blade will be latched in its raised position as above described. The stencil carrying frame will be swung upwardly by means of the treadle 80. The web W will then be fed along the desired amount to bring the next desired indicating mark on the web-carrying belt into registry with the mark on the table top 10. This procedure will be continued until the web has been completely unrolled from the feed spool, and wound up on the take-up spool.

After the spool of unstenciled web has been unwound from the feeding spool, printed, and wound up on the take-up spool, the latter may be unlocked and rolled away from the printing apparatus for drying or other treatment. It will then be returned to the printing apparatus on either side thereof, if desired, and the previous take-up roll will then serve as the feed roll—it being merely necessary to shift the crank handle 30 to the other shaft 23 to operate the feeding mechanism and take-up mechanism, as described above.

In instances where the spacer strips 101 and 102 are not cemented or otherwise secured to the carrier belt 100, a pair of fixed spaced vertical belt guiding arms 180 and 181 (see Figure 9) are provided at both ends of the table 10 to insure that the edges of the belt 100 carrying the web

W, when they leave the table 10, will properly feed between the end flanges of the spool 195. The vertical belt guiding arms 180 and 181 are secured in position by screws 182.

In the modified form of the invention shown in Figures 10 and 11, an air drying apparatus is disclosed comprising a motor 190 which is provided with a pulley 191, which by means of a belt 192 drives a larger pulley 193 loosely mounted upon a hollow shaft 194, the axis of which is aligned with the axis of the spool 165 rigidly mounted on said shaft 194.

Connected with the pulley 193 are a series of inclined radial fan blades 195 (six in this instance) which are housed within a cylindrical shield 196 having a wire protecting screen 197 at the end thereof. The shaft 194 is journaled within a pair of bracket members 198, each having an elongated base seated upon a frame 199 of trapezoidal shape, the base 200 of which is larger than the top 200a, said frame 199 being connected by side bottom bars 200b which are mounted upon rollers or casters 136.

The spool 165 is also provided with a plurality of cross bars 201 (six in this instance), which are connected at their opposite ends to a pair of circular plates 202, one of said cross bars 201a being provided with a narrow slot 203 for receiving the end of a carrier belt 204 for detachably holding said belt upon said spool. In order to guide the edges of the spiral belt 204 and hold them in alignment with the printing screen, the spool plate 202 adjacent the fan is provided with a plurality of round radial spokes 205 (six in this instance) which are connected to said circular plate. A similar number of spokes 205 are secured on an outer movable plate 205a which is held in any desired adjusted position on the shaft 194 by a set screw 205b (Figure 11a).

The pitch of the fan blades 195 is preferably made adjustable by providing cylindrical extensions 206 on their inner ends, which are adapted to be rotatably seated in socket members 207 formed on the pulley 193. The fan blades 195 are adapted to be held in any desired angular positions by means of set screws 208 engaging said extensions 206 (see Figure 11).

The modified form of the carrier belt spacing strip 210, shown in Figures 12 and 13, is similar in all respects to the strips 101 and 102 of Figures 5 and 6, except that the belt strip 210 is provided with a plurality of spaced elliptical-shaped buttons 211 secured to the bottom surface thereof, and arranged longitudinally so as to provide a streamlined construction permitting the maximum flow of air from the drying fan through the layers of the web-carrying belt spirally wound upon the spool 165.

It is also within the scope of the invention to emboss the buttons 211 upon or attach them directly to the belt 210, if desired.

In the modified form shown in Figures 14 and 15, provision is made of a web supporting belt 215 and a pair of spacing strips 216 formed separately therefrom and unattached thereto. Each strip 216 has a row of elliptical spacing buttons 217, similar to the buttons 211, shown in Figures 12 and 13, secured thereto, and said spacing strips are adapted to be passed beneath the table top 218 during the printing operation, while the web-carrying belt 215 passes above it. The strips 216 are guided under the table top 218 by a small circular flange 219 rigidly mounted on a cross rod 220 and a small movable adjustable flange 221 frictionally mounted on said cross rod. The

cross rod is secured in position below the table top 218 by a pair of angle brackets 222 attached at opposite ends of said table by screws 223.

The belt 215 is held in alignment with the printing screen by means of a pair of large guide flanges 224 mounted on a cross rod 225 secured in place by a pair of brackets 226 having ears 227 engaging the ends of said cross rod 225.

While there have been disclosed in this specification several forms in which the invention may be embodied, it is to be understood that these forms are shown for the purpose of illustration only, and that the invention is not to be limited to the specific disclosures, but may be modified and embodied in various other forms without departing from its spirit. In short, the invention includes all the modifications and embodiments coming within the scope of the following claims.

Having thus fully described the invention, what is claimed as new and for which it is desired to secure Letters Patent is:

1. In a spool for a color printing apparatus, a web-carrying belt adapted to be wound spirally on said spool, marginal spacing means secured to said belt to protect the web from contact with the adjacent layer of said belt and provide a spiral drying space for said web, and means to direct a stream of dry air through the spiral space between the successive layers of said belt and web, said means including a hollow casing forming at one end of said spool, said casing having an inlet for said air stream and a plurality of spirally arranged outlet openings in alignment with said spiral spaces in the belt coiled in said spool.

2. In a screen color printing apparatus, a printing table, a spool having a web carrier belt wound spirally upon it, marginal spacing means located between the successive layers of said belt to provide a spiral drying space for said web, and means to pass a stream of air through said spiral drying space parallel to the axis of said spool, said means including a fan having adjustable blades mounted for rotation on the axis of said spool, and means for driving said fan.

3. In a screen color printing apparatus, a printing table, a spool having a web carrier belt wound spirally upon it, marginal spacing means located between the successive layers of said belt to provide a spiral drying space for said web, and means to pass a stream of air through said spiral drying space parallel to the axis of said spool, said means including a fan mounted for rotation on the axis of said spool, and means for driving said fan.

4. In a screen color printing apparatus, a printing table, a spool having a web carrier belt wound spirally upon it, marginal spacing means located between the successive layers of said belt to provide a spiral drying space for said web, and means to pass a stream of air through said spiral drying space parallel to the axis of said spool, said means including a fan mounted for rotation on the axis of said spool, means for driving said fan, and a protective end screen surrounding the periphery and end of said fan.

5. In a screen color printing apparatus, a printing table, a spool having a web carrier belt wound spirally upon it, marginal spacing means located between the successive layers of said belt to provide a spiral drying space for said web, and means to pass a stream of air through said spiral drying space parallel to the axis of said spool, said means including a fan mounted for rotation

6. In a screen color printing apparatus, a printing table, a spool having a web carrier belt wound spirally upon it, marginal spacing means located between the successive layers of said belt to provide a spiral drying space for said web, and means to pass a stream of air through said spiral drying space parallel to the axis of said spool, said means including a fan mounted for rotation on the axis of said spool, means for driving said fan, and a protective end screen surrounding the periphery and end of said fan.

7. In a screen color printing apparatus, a printing table, a spool having a web carrier belt wound spirally upon it, marginal spacing means located between the successive layers of said belt to provide a spiral drying space for said web, and means to pass a stream of air through said spiral drying space parallel to the axis of said spool, said means including a fan mounted for rotation

on the axis of said spool, means for driving said fan, and a protective end screen surrounding the periphery and end of said fan, said spool having two sets of radial spokes at the opposite ends thereof to guide the web-carrying belt into alignment with the printing screen on said table.

6. In a screen color printing apparatus, a printing table, a spool having a web carrier belt wound spirally upon it, marginal spacing means located between the successive layers of said belt to provide a spiral space for said web, means to pass a stream of air through said spiral drying space parallel to the axis of said spool, said means including a fan mounted for rotation on the axis of said spool, means for driving said fan, and a protective end screen surrounding the periphery and end of said fan, said spool having two sets of radial spokes at the opposite ends thereof to guide the web-carrying belt into alignment with the printing screen on said table, one of said sets of radial spokes being adjustable lengthwise of the axis of said spool to accommodate different widths of carrier belts.

7. In a screen color printing apparatus, a printing table, a spool, a web-carrying belt wound spirally upon said spool, a pair of spacer bands located between the successive layers of said belt and having spacing buttons on one side thereof, means to guide the belt across the top of said table in alignment with the printing screen, and means to guide the spacer bands beneath said table, said spacer band guiding means including a pair of angle brackets secured underneath said table at opposite ends thereof, a cross rod mounted in the vertical legs of said angle brackets, and two pairs of spacing flanges mounted on said cross rod, said flanges embracing the edges of said bands.

8. In a screen color printing apparatus, a printing table, a spool, a web-carrying belt wound spirally upon said spool, a pair of spacer bands located between the successive layers of said belt and having spacing buttons on one side thereof, means to guide the belt across the top of said table in alignment with the printing screen, and means to guide the spacer bands beneath said table, said spacer band guiding means including a pair of angle brackets secured to said table underneath opposite ends thereof, a cross rod mounted in said angle brackets, and two pairs of spacing flanges mounted on said cross rod and embracing the edges of said bands, one flange of each pair being frictionally and slidably mounted on said cross rod.

9. In combination, a spool for a color printing apparatus, a web-carrying belt adapted to be wound spirally on said spool, marginal spacing means between adjacent convolutions of said belt to protect the web from contact with the overlying convolutions of said belt and provide a spiral drying space for said web, and means on the spool to direct a stream of a drying medium through said space in a direction parallel to the axis of said spool.

10. A combination as set forth in claim 9 wherein the means for directing the drying medium comprises a perforate flange on said spool and means to supply the drying medium under pressure to the outer surface of said flange.

11. In combination, a spool for a color printing apparatus, means to mount such spool for rotation about a horizontal axis, a web-carrying belt adapted to be wound spirally on said spool, marginal spacing means between adjacent convolutions of said belt to protect the web from contact with the overlying convolutions of said belt and provide a spiral drying space for said web, and means on the spool to direct a stream of a drying medium through said space in a direction parallel to the axis of said spool.

12. A combination as set forth in claim 11 wherein the spool has perforate flanges against the outer face of one of which the drying medium is supplied under pressure, the outer facing of the other of the flanges being exposed to atmospheric pressure.

13. A combination as set forth in claim 11 wherein the means for directing the drying medium comprises a perforate flange on said spool and a fan mounted for rotation coaxially of said spool and adjacent to the outer surface of said flange.

14. A combination as set forth in claim 11 wherein the means for directing the drying medium comprises a perforate flange on said spool and a set of fan blades journaled for rotation on the rotative mounting means for said spool.

15. A combination as set forth in claim 11 wherein the means for directing the drying medium comprises a hollow casing forming one of the flanges for the spool, the wall of the casing facing the web being perforate, and wherein means is provided to supply the drying medium under pressure to said casing.
